United States Patent Office.

SOLOMON C. SPRING, OF BRISTOL, CONNECTICUT, ASSIGNOR TO WELCH,
SPRING, AND COMPANY, OF SAME PLACE.

Design No. 3,211, dated September 22, 1868.

DESIGN FOR A CLOCK-CASE.

The Schedule referred to in these Letters Patent and making part of the same.

TO ALL WHOM IT MAY CONCERN:

Be it known that I, SOLOMON C. SPRING, of Bristol, in the county of Hartford, and State of Connecticut, have originated and designed a new Design for a Clock-Case, of which the following is a full, clear, and exact description, reference being had to the accompanying photographic views or drawings, making a part of this specification.

Similar letters of reference indicate like parts.

a designates a round bead extending across the top of the front and sides of the base. Immediately beneath the rounded bead *a* is a series of sharp beads, which form a series of alternate ribs and channels, *b*, and then another rounded bead *a*, which compose the top of the base.

On each corner, between the top and base, is an upright rounded bead, *A*, and a series of alternate ribs and channels, *B*, and then a bevelled plane surface, *C*.

The sash is composed of a series of alternate upright ribs and a channel, *B*, and a rounded bead, *A*.

On the sides of the case the panel is composed of two series of alternate upright ribs and channels *B*, with a plane surface, *D*, between them.

The base of the case is first a transverse rounded bead, *a*, then immediately beneath it is a series of alternate ribs and channels, *b*, then another series of larger alternate ribs and channels *c*, then a rounded bead, *a*, and lastly, another series of alternate ribs and channels *b*, the whole combined to produce a neat and rich design for a clock-case.

What I claim as my invention, and desire to secure by Letters Patent, is—

The design for a clock-case herein shown and described.

SOLOMON C. SPRING.
